ADVERTISING CONDIMENT SHAKER

Emery N. Sarber, Vancouver, British Columbia,
Canada

Application January 18, 1934, Serial No. 707,194

1 Claim. (Cl. 40—19)

This invention relates to improvements in salt shakers and like containers, such as are used on the tables in hotels, restaurants and other public eating places for holding salt and pepper and the like.

My invention is designed for the dual purpose of acting as a container for salt or pepper and displaying advertising matter continuously and in such a manner that the advertising copy is fully

10 protected from becoming soiled or unlegible.

An object of my invention has been to provide a new and novel way of displaying advertising copy in public eating places.

15 A further object of my invention has been to provide a neat, attractive, sanitary and efficient container and shaker for salt or pepper.

20 A still further object of my invention has been to provide a salt or pepper shaker having means for instant change of advertising copy without the necessity of emptying the container before effecting an advertising change.

25 Still another object of my invention has been to provide an attractive shaker economical to manufacture, so as to provide for practically free distribution to hotels, restaurants and other public eating places to enable the display of advertising copy therein.

With these and other objects in view I have invented the improved shaker and container which 30 is the subject matter of this application and which is further described in the accompanying drawing, in which:

35 Figure 1 is an elevation of an improved shaker showing a device completely assembled ready for use with salt or pepper within the inner container and an advertising label secured thereupon; a sight line is left on the inner container between the ends of the advertising label.

Figure 2 is a cross sectional elevation of the device showing all essential parts and features.

40 Figure 3 is a view of the advertising label in a plan showing a row of perforations that form the sight line to the contents of the inner container when the label is secured thereupon.

45 Figure 4 is a view of the advertising label formed into a cylinder for slipping upon the inner container.

50 In the drawing like numerals indicate like parts, and the numeral 1 indicates a glass container having a screw-threaded top 2 and a perforated cover 3 fitting same.

Fitting inside the container 1 is a parallel-sided inner container 4 having an open top 5 and a concentric flange 6 formed therearound.

55 The inner container 4 is adapted for being

secured within the outer container 1 by being supported by the flange 6 on the top rim 7 of the outer container and being compressed thereupon by the perforated cover 3.

The inner container is the one containing the ingredients with which the shaker is to be used, i. e., salt or pepper or the like, and the one on which the advertising medium is secured.

5 The advertising medium is in the form of labels 8 of a size adapted to fit around the inner container 4 and may be used in the form of cylinders 9, as shown in Figure 4, whereby they are adaptable for slipping on and off the inner container 4 to enable a quick change of advertising copy to be made, or they may be used after the manner indicated in Figure 1, whereby they are pasted or gummed around the parallel side walls of the inner container and a sight line 10 left between the ends of the label for observing the amount of contents 11 of the inner container.

10 If the labels 8 are to be formed into cylinders 9, then it is preferable to have means of ascertaining the contents of the inner container 4, and to this end a series of perforations 12 is provided in the labels 8 to form a sight line 10.

15 By placing the advertising matter within the outer container the copy is protected from becoming soiled or defaced. The device provides a constant and effective reminder of the advertiser and his goods, and the construction of the device 30 enables a quick change of advertising matter to be made.

20 As will be observed, the advertising matter is at no time in contact with the contents of the shaker and therefore no contamination of the 35 same is possible.

A particular advantage is that change of advertising matter may be effected without emptying the contents of the shaker.

Having now described my invention and the 40 nature of same, what I claim and desire to be protected in by Letters Patent, is:

45 In a salt or pepper shaker adapted for displaying advertising copy comprising in combination with such advertising copy, an inner and outer container of transparent material, said inner container having an open top for receiving therein salt or pepper and a concentric flange formed around said open top and extending to and overlying the mouth of the outer container 50 for supporting and securing said inner container within the outer, parallel side walls on said inner container adapted for receiving thereupon said advertising copy, said advertising copy having a series of perforations therein whereby the con- 55

tents of said inner container may be observed when said advertising copy is secured around the body of said inner container, a perforated cover fitting said outer container and over the concentric flange of said inner container whereby said cover secures said inner container within

the outer one by compression upon said concentric flange when said cover is secured upon said outer container, and means for securing said cover upon said outer container.

EMERY N. SARBER.
